US00D611539S

(12) **United States Design Patent**
Zhang

(10) **Patent No.:** **US D611,539 S**
(45) **Date of Patent:** **** Mar. 9, 2010**

(54) **PEN**

(75) Inventor: **Biwei Zhang**, Ningbo (CN)

(73) Assignee: **Beifa Group Co., Ltd.**, Ningbo (CN)

(**) Term: **14 Years**

(21) Appl. No.: **29/330,735**

(22) Filed: **Jan. 13, 2009**

(30) **Foreign Application Priority Data**

Jul. 25, 2008 (CN) 2008 3 0138506

(51) **LOC (9) Cl.** **19-06**

(52) **U.S. Cl.** **D19/51**

(58) **Field of Classification Search** ..... D19/35, D19/36, 41-51, 53-57; 24/11 F, 11 P, 11 R; 401/52, 99, 100, 104-109, 192, 195, 196
